UNITED STATES PATENT OFFICE.

LOUIS KYSER AND ALFRED C. REX, OF PHILADELPHIA, PENNSYLVANIA.

TOY GARDENING-TOOL.

SPECIFICATION forming part of Letters Patent No. 240,257, dated April 19, 1881.

Application filed January 6, 1881. (No model.)

To all whom it may concern:

Be it known that we, LOUIS KYSER and ALFRED C. REX, of the city of Philadelphia, county of Philadelphia, and State of Pennsylvania, have invented an Improvement in Toy Gardening-Tools, &c., of which the following is a specification.

Our invention relates to the construction of gardening and other tools; and it consists in so constructing the blade or working part and handle upon a shaft that the said shaft shall fit into sockets upon such parts, which sockets shall be made with uncored holes, all of which will be fully set forth in the specification hereunto annexed, shown in the accompanying drawings, and referred to in the appended claims.

Heretofore these and similar toys have had the sockets cast hollow with cored holes, which construction was very expensive, and the handles have been made of wood and attached to or forming part of the shaft.

Our object is to lessen the cost, as much as possible, by so constructing the parts that there shall be a lessened expense in their production; further, that the handle shall be made separate from the shaft, and secured thereon by means of an uncored socket.

In the drawings, Figure 1 is a perspective view of a toy spade, embodying in it our invention. Fig. 2 is a side elevation of same, with part of blade in cross-section and a portion of the shaft broken away. Fig. 3 is a cross-section of same on line *x x* of Fig. 1, looking toward the blade.

A is the blade, *B* the shaft, and *C* the handle. To *A* is secured, or cast with it, a socket-piece, *D*, connected to it by neck *G*. This socket-piece *D* is constructed of substantially three bars cast in one piece, *F*, *H*, and part of neck *G*. The three bars are connected together at either end, thereby leaving a space in the socket opposite to each bar, as shown in Fig. 2, in which the space *d* is opposite the bar *H*.

By this construction it is evident that it will not be required to use a core in making the sockets of the castings, since there is only a single piece of metal to be molded between the

mold-boxes forming the flask in any one vertical line. In looking at the end of the sockets they will appear perfectly round, and when the shaft *B* is inserted therein it will be held in position by the bars. That part of the shaft opposite any one bar is exposed, as shown. 50

By this construction the cost of producing toy gardening-tools and analogous articles is much reduced over the old method of using cored sockets; further, it is an easy matter to secure the shaft in the socket without drilling 60 holes through the same for the insertion of pins, for we simply drive a small nail into the shaft on the side immediately opposite the bar, and through the open part in the casting in the socket, as shown at *L* and *M*. 65

Having now described our invention, what we claim as new, and desire to secure by Letters Patent, is—

1. As a new article of manufacture, a gardening-tool or analogous article consisting of 70 the blade *A*, or its equivalent, socket *D*, composed of the bars *F*, *H*, and *G*, having spaces immediately opposite them, said bar *G* being extended and secured to the blade, shaft *B*, secured in the said socket *D*, and handle *C*, of 75 cast-iron, provided with a socket, *E*, composed of bars *I* *J* *K*, and spaces immediately opposite said bars, the said socket being firmly secured upon the shaft, substantially as and for the purpose specified. 8c

2. As a new article of manufacture, a gardening-tool or analogous article consisting of the blade *A*, or its equivalent, socket *D*, composed of the bars *F*, *H*, and *G*, having spaces immediately opposite them, said bar *G* being 85 extended and secured to the blade, and shaft *B*, secured in the said socket *D*, substantially as and for the purpose specified.

3. A blade of a gardening-tool or its equivalent, in combination with an uncored socket 90 secured to the same, which socket consists, substantially, of bars *F* *H* *G*, and openings directly opposite said bars, whereby the whole may be cast in one piece, substantially as and for the purpose specified. 95

4. As a new article of manufacture, a toy gardening-tool consisting of the blade *A*, attached to and forming part of an uncored

socket, D, shaft B, and a handle, C, secured to shaft B by socket E, said blade and handle being kept upon the shaft by pins or nails L M, driven in said shaft through the openings 5 in the socket immediately opposite the bars of the same, substantially as and for the purpose specified.

In testimony of which invention we hereunto set our hands.

LOUIS KYSER.
ALFRED C. REX.
